Patented Mar. 23, 1976

239,221

TOOTHBRUSH

Bernard Wasserman, 38 Rose Ave.,
Great Neck, N.Y. 11021

Filed Mar. 19, 1975, Ser. No. 559,849

Term of patent 14 years

Int. Cl. D4—02

U.S. Cl. D4—25

FIG. 1

FIG. 2

FIG. 3

FIG. 4

FIG. 5

FIG. 6

FIG. 1 is a side elevational view of a toothbrush, showing my new design.

FIG. 2 is a top plan view thereof.

FIG. 3 is a bottom plan view thereof.

FIG. 4 is a left end elevational view thereof.

FIG. 5 is a right end elevational view thereof.

FIG. 6 is a cross-sectional view taken along the line 6—6 of FIG. 1.

I claim:

The ornamental design for a toothbrush, as shown.
